UNITED STATES PATENT OFFICE.

WILLIAM A. MELBOURNE, OF SWANWICK, ILLINOIS.

TELEGRAPH KEY AND INSTRUMENT.

SPECIFICATION forming part of Letters Patent No. 378,332, dated February 21, 1883.

Application filed October 15, 1887. Serial No. 252,443. (No model.)

To all whom it may concern:

Be it known that I, WILLIAM A. MELBOURNE, a citizen of the United States, residing at Swanwick, in the county of Perry and State of Illinois, have invented certain new and useful Improvements in Telegraph Keys and Instruments; and I do hereby declare the following to be a full, clear, and exact description of the invention, such as will enable others skilled in the art to which it appertains to make and use the same.

This invention relates to an improvement in telegraph keys and instruments; and it consists in the arrangement of the key with two main lines so as to enable it to be thrown into the circuit of either, and, further, in certain details of the combination and arrangement of the several parts of the device, substantially as will be hereinafter specified, and then 20 pointed out in the claims.

In the accompanying drawings, illustrating my invention, Figure 1 is a side elevation of my improved telegraph key and instrument. Fig. 2 is a top plan view of the same. Fig. 3 is an interior view of the bottom of the base, showing the arrangement of the parts in said base when the key is in circuit with one of the main lines. Fig. 4 is a similar view showing the arrangement of parts when the key is in 30 the circuit of the other main line. Fig. 5 is a transverse section on the line $x-x$ of Fig. 4.

Similar letters of reference designate corresponding parts in all the figures.

A denotes a hollow box, base, or casing of any desired shape and size, and consisting, 35 preferably, of a top, upon which the key is mounted, and a bottom, as A', said top and bottom being suitably secured together and having an inner space between them, which is 40 occupied by the parts of my device, whereby the key is placed in circuit with either one or the other of the main lines.

B represents the key. It consists of a strip of steel or other spring metal or substance, 45 provided on one end with the usual insulated finger-button, while the other end is curved or bent back upon itself, the extremity being rigidly secured to the base A.

A vertical screw-threaded post, C, fastened 50 upon the top of the base A, passes through a perforation in the metallic strip B, and car-

ries a nut, a, which bears upon the key from above, and in consequence of the rotation of which said key may be adjusted upward or downward, so as to locate the projection b on 55 the under side thereof the proper distance from the contact c on the base. It will be readily seen that the spring metal of which the key is composed gives it the tendency to move upward, a tendency which is effected in 60 the common key by means of springs, &c. Adjacent to the key upon casing A is a switch, D, by the proper manipulation of which the operator can cause the key to serve as a transmitter. Upon the casing are also located the 65 binding-posts E E' E'' E'', two of which, E and E', receive the wires of main line No. 1, and the other two, E'' and E'', the wires of main line No. 2. By means of these posts the wires are connected with the instrument.

Within the hollow box or base is located longitudinally a rotative switch consisting of a rod, F, which projects through an opening in one end of the base and is provided with a lever-handle, F', secured to this exposed end, 75 whereby the switch is manipulated. A flat spring, G, fastened at one end to bottom A', bears within a circumferential groove on the switch-rod F and serves to hold it fixed in any position to which it may have been rotated. 80 Suitable grooves on the interior of the hollow base guide the rod in the desired manner.

Secured to base A' transversely to the rod F, and with a certain portion of each of them beneath said rod, are eight metallic strips, H 85 I J K L M N O, preferably of brass. One way of arranging these strips, which I have found it convenient to adopt, is shown in the example of my invention illustrated in the drawings. (See Fig. 5.) Here a longitudinal 90 groove is cut in base A' beneath rod F. The strips H I J, &c., are each secured to the base A' at one end, with their free ends projecting partially across this groove. The rod F rests upon these free ends, and the spring G serves 95 to hold said rod close down upon the strips, which are thereby caused to bend more or less, and thus their own tension helps to maintain a permanent and unbroken contact with the rod F, or rather the plates thereon, to be hereinafter spoken of.

The rod F is provided on two longitudinal

lines thereof with two series of three plates each. One of these lines will be on the bottom of the rod when the handle F' is vertical or in the position shown in the plan, Fig. 4, 5 and the other line when the rod is in the same position will be on the outer side of said rod. The three plates on the under side of the rod when in position shown in Fig. 4 are lettered g, h, and i, and they are so positioned relatively to each other and the plates H I J, &c., that plate g will rest upon and establish a connection between plates I and J, plate h will rest upon and connect plates L and M, and plate i will similarly rest upon and connect plates N and O. The other series of three plates are designated k, l, and m. When the switch-rod has been rotated to the position in Fig. 3, where handle F' is in a position at right angles to that in Fig. 4, these plates k, 20 l, and m will be on the bottom of the switch-rod, and they are so positioned on said rod relatively to each other, to the plates H I J, &c., and the plates g h i that when the switch-rod is in the position of Fig. 3 plate k will rest upon and establish a connection between plates H and I, plate l will rest upon and connect plates J and K, and plate m will similarly rest upon and connect plates M and N. It will thus be seen how a quarter-revolution 25 of the rotative switch-rod will change the connections between the different plates and afford different paths for the electrical current. The two wires of main line No. 1 connect with the binding-posts E and E', as already 30 stated. Inside the casing a wire, o, passes from post E to plate M. The connection with plate M, as likewise the connection of the wires with all the eight plates, is made by twisting the end of the wire about a screw on 35 the plate; but I do not intend to confine myself to this mode of connection, as various others may be devised. From the post E' a wire, p, extends to plate N. The wires of main line No. 2 connect with binding-posts E' 40 and E'', a wire from post E'', as q, passing to plate I, and a wire from post E', as r, passing to plate J. The contact-point c beneath the key connects with plate H by a wire which passes on, as s, and makes a connection with 45 plate L. The key itself has connection with plate O, and also plate K, by a wire, t, passing from key to plate O and then between plates O and K. Obviously considerable variations may be made in the mode of arranging 50 these wires, provided that they are so placed that the electrical current will flow in substantially the same way as that permitted by 55 the present arrangement.

From this description of the construction of 60 the instrument and the internal arrangement of the plates and wires it will be readily understood how the switch-rod F is to be manipulated for the purpose of allowing the key to be in the circuit of line No. 1 or of line No. 2. 65 Suppose it is desired to use the instrument in connection with line No. 1. The operator

grasps the handle F' of the switch and places it in a perpendicular position. (See Fig. 4.) The plates g, h, and i will now form connections with the plates on the base, as already 70 specified. The course of current in main line No. 1 will therefore be as follows: Passing through one of the main wires to binding-screw E, it will flow along wire o to plate M, thence through connecting-plate h to plate L, 75 along wire s to plate H and the contact c. From the key it will run into plate O, across connection i into plate N, and then by wire p into the other wire of line No. 1, that reaches the instrument at binding-screw E'. This arrangement of parts is seen in Fig. 4. The circuit of line No. 2 will at this time be closed and the current will pass from screw E' through wire r to plate J, plate g, plate I, and wire q to screw E''. 85

When it is desired to use main line No. 2, the operator will move handle F' until it lies in a horizontal position, as seen in Fig. 3. The plates k l m on the rod F will now make the desired connections, as already hereinabove 90 stated. The current from wire at binding-screw E' will pass through wire q to plate I, thence across by plate k to plate H, and so to the contact c. From key current will flow through plate O into wire t to plate K, across 95 connection l into plate J, and thence by wire r to the other wire of main line No. 2. Main line No. 1 will now be closed, the current flowing from one main wire through wire p, plate N, connection m, plate M, and wire o to the 100 other main wire. In this manner the key is changed from one line to the other without obstructing either line in working, and both line-instruments working through this key can be heard working at all times. 105

Having thus described my invention, what I claim as new, and desire to secure by Letters Patent, is—

1. The combination of the casing having a base portion, the series of eight plates secured 110 to said base relatively as specified, the rotative switch-rod having two separate series of three plates each located thereon, as shown, the two main lines, the connecting-wires, and the key, substantially as described. 115

2. The rotating switch consisting of a rod having two series of three plates each arranged in longitudinal lines, in combination with the base of the casing, provided with a series of eight parallel plates with which the switch-rod plates form connections, substantially as 120 and for the purposes described.

3. The combination of a rotating switch-rod having two series of three plates each thereon, a horizontal series of eight plates which the 125 switch-rod operates to connect, as set forth, the two main lines, a suitable system of connecting-wires between the plates and the main lines, and the key, substantially as described.

4. The combination of the hollow base, the 130 rotative switch-rod provided with plates, the horizontal series of plates beneath the switch-

rod, the connecting-wires between the plates, the two main lines, the key, and connections between them, substantially as described.

5. The combination of the hollow base, the key mounted thereon, the rotating switch within the casing, provided with a suitable handle operating in suitable guides and kept in place by a spring within the casing, and the series of eight parallel plates beneath the switch, 10 the connecting-wires, and the two main lines, all substantially as described.

6. The combination of hollow base A, having

base A', the eight plates H I J K L M N O, secured to said base, the switch-rod F, provided with plates g h i and k l m, the two main lines, 15 connecting-wires, and key, substantially as described.

In testimony whereof I affix my signature in presence of two witnesses.

WILLIAM A. MELBOURNE.
